US00D626932S

(12) **United States Design Patent**
Kim et al.

(10) **Patent No.:** US D626,932 S
(45) **Date of Patent:** ** Nov. 9, 2010

(54) **MOBILE PHONE**

(75) Inventors: **Bo-Ra Kim**, Seoul (KR); **Sang-Min Hyun**, Seoul (KR); **Nam-Mi Kim**, Seoul (KR)

(73) Assignee: **Samsung Electronics Co., Ltd.** (KR)

(**) Term: **14 Years**

(21) Appl. No.: **29/350,916**

(22) Filed: **Nov. 25, 2009**

(30) **Foreign Application Priority Data**

Oct. 9, 2009 (KR) 30-2009-0044399

(51) **LOC (9) Cl.** **14-03**

(52) **U.S. Cl.** ..... **D14/138 AB**

(58) **Field of Classification Search** ..... D14/138 AB, D14/496, 341, 345, 346, 203.3, 203.4, 203.7; 455/575.3; D21/517; 379/433.13

See application file for complete search history.
